UNITED STATES PATENT OFFICE.

HARTVIG SORLEY, OF MACOMB, ILLINOIS.

CREEPER.

1,232,114.

Specification of Letters Patent.

Patented July 3, 1917.

Application filed January 21, 1916. Serial No. 73,420.

To all whom it may concern:

Be it known that I, HARTVIG SORLEY, a citizen of Norway, residing at Macomb, in the county of McDonough and State of Illinois, have invented certain new and useful Improvements in Creepers, of which the following is a specification.

This invention has relation to certain new and useful improvements in creepers and relates more specifically to devices of the character intended for use by painters, carpenters and the like and known as roof creepers.

The invention has for its primary object, the provision of a creeper which may be readily clamped upon the shoe and adjusted for use upon inclined roofs or similar surfaces, the device being adjusted according to the pitch of the roof or angle of the inclined surface.

10. The invention has for a further object the provision of a creeper of this character which will be of simple construction, may be readily adjusted and will be highly efficient in use.

25. With the above and other objects in view, the invention resides in the novel construction, combination and arrangement of parts as will be hereinafter more specifically set forth, pointed out in the claims, and shown 30 in the drawings, in which,

Figure 1 is a side elevation of the complete device in use, and,

Fig. 2 is a bottom plan view, partly in section, as indicated by the line 2—2 of 35 Fig. 1.

Referring more particularly to the drawings in which similar reference characters designate corresponding parts throughout the several views, 1 designates the tray with 40 in which the shoe of the operator may be securely clamped by means of a pair of clamping straps 2 adapted to be adjusted and secured over the shoe, as indicated in Fig. 1. The tray 1 is pivoted at its narrow 45 forward end upon the pivot pin 3 which extends through the forward ends of the longitudinal frame members 4 and the upturned ends 5 of the front creeper plate 6 which has a depending toothed edge 7. The 50 longitudinal frame members 4 have their opposite ends secured to the upper ends of the rear frame members 8 which are preferably formed of angle iron and have the rear creeper plate 9 secured to their lower ends 55 and provided with a depending toothed edge

10. By forming the rear of the frame members 8 of angle iron and bending the ends of the longitudinal frame members, a rigid connection may be made between said frame members 4 and 8. The curved or arcuate intermediate frame members 11 are also secured at their upper ends to the upper ends of the frame members 4 and 8 and the intermediate frame members 11 have secured to their lower ends the intermediate brace 65 member 12. The intermediate frame members 11 are also preferably formed of angle iron and are braced by suitable brace bars 14 connecting the lower ends of the same with the intermediate portions of the rear 70 frame members 8. Brace bars 15 are also provided to connect the brace bars 14 with the longitudinal frame members 4 to further brace the frame.

The intermediate frame members 11 are 75 provided in their front faces with suitable openings 16 within which are normally engaged the turned ends 17 of the latch member 18. The latch member 18 extends transversely beneath the heel receiving portion 80 of the tray 1 and has its main portion provided with a central extension 19 projecting rearwardly through the guide 20 secured upon the guide plate 23 which in turn is secured to the bottom of the tray 1 and provided with suitable guide openings for the intermediate frame members 11, as will be 85 readily seen by referring to Fig. 2 of the drawings. The latch member 18 is resiliently retained in operative position, by 90 means of the leaf spring 21 secured by its central portion to the guide 20 and having its curved ends pressing against the main portion of said latch member 18. A suitable covering and protecting plate 22 is 95 also secured to the under face of the tray 1 and has an offset portion extending over the main portion of the spring 21 and adjacent end of the guide 20, as shown in Fig. 1 of the drawings.

100 From the foregoing it will be readily seen that the tray 1 may be adjusted in the supporting frame by forcing inwardly the extension 19 to disengage the ends 17 of the latch member 18 from the openings 16 and 105 swinging the tray 1 upon its forward end, permitting the spring 21 to return the latch member 18 to operative position for the purpose of locking the tray 1 in adjusted position.

While the preferred embodiment of the invention has been shown and described, it will be understood that minor changes in the construction and arrangement of parts 5 may be resorted to within the scope of the appended claims without departing from the spirit of the invention or sacrificing any of the advantages of the same.

I claim:

1. In creepers, the combination with a frame including intermediate curved members, of a shoe receiving tray pivoted in said frame and having one end extended between said intermediate curved members, means 10 carried by said shoe receiving tray and projecting from the sides thereof having bent ends for locking engagement in said curved members of the frame, means for resiliently retaining the last mentioned means in operative position, means for guiding said shoe receiving tray upon said intermediate curved frame members, surface gripping plates carried transversely of said frame, and means carried by said shoe receiving tray to secure 15 a shoe therein with the sides of said tray surrounding the sides and ends of said shoe.

2. In creepers, the combination with a frame including intermediate curved members, of a shoe receiving tray pivoted in the 20 forward end of said frame, guide members carried by said tray and projecting to the sides of the same for sliding movement upon said intermediate curved members, said intermediate curved members having openings formed therein, a locking member carried by said tray and having projecting bent ends for engagement in said openings to support said tray in adjusted position, and means for withdrawing said ends from said 25 intermediate curved members.

3. In creepers, the combination with a frame including forward members and rear inclined members, said forward members and rear inclined members extending at substantially right angles to one another to 30 form the upper angles of the substantially triangular frame, of transverse surface engaging plates secured to the lower ends of said frame members and provided with serrated lower edges, curved intermediate frame members secured by their upper ends to the first mentioned frame members at the point of connection of the same at the upper corner of the frame, said curved intermediate frame members having outwardly directed side portions, a guide plate slidably mounted on said intermediate curved frame members, a shoe receiving member mounted upon said guide plate and having 35 its forward end pivoted between the lower ends of the forward inclined frame members, said shoe receiving member having an annular flange for engagement with the ends and sides of a shoe engaged in said shoe receiving member, means for securing the shoe 40

in said shoe receiving member, and means for locking said guide member in adjusted position upon said intermediate curved frame members.

4. In creepers, the combination with a frame and a shoe surrounding member pivoted in said frame; of a guide plate mounted upon the bottom of said shoe surrounding member and slidably mounted upon opposite members of said frame, a portion of 75 said shoe surrounding member extending between opposite frame members, a locking bar mounted upon said guide member, said opposite frame members having bolt openings formed therein, the ends of said locking bar being bent to form locking bolts, means for guiding said bar upon said guide member, and means positioned upon said guide member and having opposite ends engaged with said bar adjacent the ends of the same to resiliently retain said ends in said bolt openings and lock the shoe surrounding member in adjusted position within said frame.

5. In creepers, the combination with a frame formed of oppositely inclined side members arranged in pairs and connected at their upper ends to form the upper corner of the frame, of transverse surface engaging plates connecting the lower ends of the 90 opposite side frame members and having serrated lower edges to provide spaced teeth for biting engagement with the inclined surface, intermediate frame members depending from the upper corner of said frame, means for connecting the lower ends of said intermediate frame members with the inclined side frame members and bracing the sides of the frame, a receptacle pivoted by its forward end in the forward end of the frame and having its rear end adjustably mounted between said intermediate frame members, said receptacle being adapted to receive and surround a shoe, means for securing a shoe within said receptacle, and means carried by said receptacle to lock the rear end of the same in adjusted position between said intermediate frame members.

6. In a device of the character described, a creeper plate, a foot receiving tray pivotally connected therewith and provided with openings at its rear end, side bars connected with the creeper plate, a pair of legs carried by the side members and extending through the openings in the tray, a second pair of legs carried by the side bars, and latch means carried by the tray and engaged with the last mentioned legs to support the tray.

7. A device of the character described comprising a frame, a foot receiving tray having its forward end pivotally connected with the frame, the frame including parallel supporting legs having openings therein, a locking bar arranged upon the under face of the tray and having lugs upon its extremities,

and resilient means urging the bar to a position to engage the lugs into certain of the openings.

8. A device of the character described comprising a frame, a foot receiving tray having its forward end pivotally connected therewith, the frame including parallel supporting legs, a plate secured to the under face of the tray, a locking bar mounted on 10 the plate and movable at right angles there-

to, and a spring bearing against one end of the plate and urging the bar into locking engagement with the supporting legs.

In testimony whereof I affix my signature in presence of two witnesses.

HARTVIG SORLEY.
